(57) **CLAIM**

I claim the ornamental design for a vibrator sleeve with multiple extensions, as shown and described.

DESCRIPTION

FIG. 1 is a front elevational view of a vibrator sleeve with multiple extensions showing my new design.

FIG. 2 is an opposing back side view thereof.

FIG. 3 is a right side view thereof.

FIG. 4 is a left side view thereof.

FIG. 5 is an upper end view thereof; and,

FIG. 6 is a bottom end view thereof.
